UNITED STATES PATENT OFFICE.

XENOPHON CAVERNO, OF KEWANEE, ILLINOIS.

DESIGN FOR A PUMP AND ENGINE BASE.

43,032.

Specification for Design.

Patented Sept. 24, 1912.

Application filed May 29, 1911. Serial No. 630,237. Term of patent 14 years.

To all whom it may concern:

Be it known that I, XENOPHON CAVERNO, a citizen of the United States, residing at Kewanee, in the county of Henry and State of Illinois, have invented a new, original, and ornamental Design for a Pump and Engine Base, of which the following is a specification, reference being had to the accompanying drawing, forming a part thereof.

The leading features of my design consist in the provision of a raised base of web form, slightly tapered upwardly and having substantially square openings E in its side walls in which angularity of outline is relieved by rounding the corners of the top A, base B and intermediate portions D, and also rounding the marginal corners E' of the

openings E, the outer surface being convexly rounded along the line 3 of connection C, between the intermediate and base portions. The interior surfaces of the intermediate portions are exposed through the openings E, and are provided with ribs F, having angular corners which contrast with the rounded outer surfaces, and add to the pleasing appearance of the structure.

I claim:

The ornamental design for a pump and engine base as shown and described.

XENOPHON CAVERNO.
